(57) **CLAIM**

The ornamental design for a cap, ring and foil for a single-serve coffee container, as shown and described.

DESCRIPTION

FIG. 1 is a top front perspective view of a cap, ring and foil for a single-serve coffee container showing my new design; FIG. 2 is a top plan view thereof;

FIG. 3 is a bottom plan view thereof;

FIG. 4 is a front elevation view thereof, with the rear, right, and left elevation views being an identical image thereof;

FIG. 5 is an exploded view thereof;

FIG. 6 is an exploded sectional view thereof taken along line 7-7 of FIG. 2 with the lid exploded above;

FIG. 7 is a sectional view thereof taken along line 7-7 of FIG. 2; and,

FIG. 8 is a detail section view thereof taken along line 8-8 of FIG. 7.
